UNITED STATES PATENT OFFICE.

HARRY E. JAMES, OF DETROIT, MICHIGAN.

CLIP FOR RULE-CASES.

1,200,946.

Specification of Letters Patent. Patented Oct. 10, 1916.

Application filed June 16, 1916. Serial No. 104,012.

To all whom it may concern:

Be it known that I, HARRY E. JAMES, a citizen of the United States, residing at Detroit, in the county of Wayne, State of Michigan, have invented certain new and useful Improvements in Clips for Rule-Cases; and I do hereby declare the following to be a full, clear, and exact description of the invention, such as will enable others skilled in the art to which it appertains to make and use the same.

The present invention is directed to improvements in clips adapted to be secured to a pocket rule case or the like, and has for its object to provide a device of this character which can be conveniently attached to the case and when engaged therewith serves to retain the case in the pocket.

A further object of the invention is to provide a clip of this character which is formed from resilient sheet metal and is constructed in such a manner that the same can be firmly engaged with the front wall of the case so that one leaf of the clip will be in a position to clamp over the flap of the pocket.

With these and other objects in view, this invention resides in the novel features of construction, formation, combination, and arrangement of parts to be hereinafter more fully described, claimed and illustrated in the accompanying drawing, in which:

Figure 1 is a view showing the device in use. Fig. 2 is a sectional view on line 2—2 of Fig. 1. Fig. 3 is a detail perspective view of the clip.

Referring to the drawing 1 indicates the case, which is of a well known form and consists of front and rear walls 2 and 3, formed from leather, and connected by the metallic frame 4.

The clip 5 is formed from a single piece of sheet metal and is bent intermediate its ends so as to provide inner and outer leaves 6 and 7, respectively. The inner leaf 7 is provided adjacent its lower edge with a pair of outwardly struck spurs 8 which are adapted to engage the inner surface of the front wall 2 of the case 1, thereby preventing disengagement of the clip from the case.

To apply the clip it is only necessary to

cut a horizontal slit 9 in the front wall 2, after which the leaf 7 of the clip can be passed through the slit so that the spurs 8 carried thereby can bite into the inner surface of the wall 2, thereby preventing accidental disengagement of the clip from the case. After the clip has been engaged with the case 1, and the case placed in the pocket the leaf 6 of the clip will yieldably engage the outer surface of the pocket flap, thereby firmly holding the case within the pocket.

From the foregoing description it will be seen that a clip has been provided which is exceedingly simple in construction and one which can be easily and quickly attached to a conventional form of rule case so as to retain the same within the pocket. It will be further noted that when the ruler is engaged in the case that it will engage the leaf 7 of the clip and serve to positively retain the spurs 8 engaged with the inner surface of the wall 2.

While the device is particularly adapted for use in connection with cases for containing rulers it is obvious that the same can be used in connection with cases of this type which are used for other purposes. It will be noted that the inner leaf is of greater length than the outer leaf, and that the end of the leaf is bent inwardly, as clearly shown in Fig. 2 so as to more firmly grip the flap of the pocket.

What is claimed is:

In a device of the class described the combination with a case having front and rear walls, of a clip formed from a single strip of resilient metal and bent upon itself to provide inner and outer leaves, the inner leaf having its entire length confined within the case, and having outwardly struck spurs carried thereby for engaging the inner surface of the front wall of the case, the outer leaf of said clip being adapted to clamp over the flap of a pocket, as and for the purpose set forth.

In testimony whereof, I affix my signature, in the presence of two witnesses.

HARRY E. JAMES.

Witnesses:

Mrs. M. E. JAMES,
LE-ROY HARCHENHORN.
